CONSTRUCTION OF HAND-OPERATED
TAPE DISPENSERS
Kenneth S. Walther, 2980 Coolidge Road,
Muskegon, Mich.
Filed Nov. 27, 1961, Ser. No. 155,095
3 Claims. (Cl. 156—523)

This invention relates to the construction of tape dispensers, and the preferred forms provide devices that can be operated with one hand to engage, apply, and cut-off tape of a variety of types. Sealing tape for closing cartons, masking tape for covering surfaces adjacent areas to be painted, and electrician's tape for insulating wire splices are examples of the material that can be handled by devices embodying this invention. The dispensers can be placed in the pocket of the workman, or hung on a convenient hook when not in use. The preferred forms are always ready for instant use. Certain components of the device facilitate the application and positioning of the tape, and the unit has a much greater field of utility than that of a mere storage magazine.

The devices include a frame acting as a container for the tape, and also a hollow cantilever extension of the frame through which the protected tape moves to the point of application. At this point, the preferred forms of the devices include a bearing member for holding the tape against a work surface, and a cut-off mechanism for severing the tape as close to the bearing member as possible. In this invention, the frame serves the purpose of a handle, with the positioning of the actuator of the cut-off mechanism such that the manipulation of it is easily performed without shifting the grip on the device, or using more than one hand. It must be kept in mind that the forces required to strip certain types of tape from the roll are considerable, and the workmen must at all times retain a very firm grip on the device in order to properly manipulate it. Actuation of the cut-off mechanism has been accommodated 40 to this condition.

The cut-off mechanism of the preferred form of the invention includes a guideway incorporated in the frame for accommodating a movable knife blade in a position to intersect the normal path of movement of the tape as it is being stripped off past the final bearing point of the device. In one modification of the device, the bearing member functioning as the last point of contact of the device against the tape is also a component of the guideway establishing the path of movement of the knife blade, and also functions in conjunction with the knife blade to provide for the removal of insulation from the end of a piece of wire.

It is important that the free end of the tape (after it has been severed by the cut-off mechanism) be properly positioned for the next application. If this is not done, it is most likely that the tape will become fouled within the interior of the frame, or be improperly located for convenient contact with the next work surface. Depending upon the nature of the tape to be applied, the invention provides arrangements for assuring that the free end of the tape is left in a projected position ready for proper application. The several features of the invention will be analyzed in detail through a discussion of the particular embodiments illustrated in the accompanying drawings. In the drawings:

FIGURE 1 presents a perspective view showing one modification of the device held in the usual position for application of sealing tape to a carton.

FIGURE 2 illustrates the same device in perspective, and showing the unit as the cut-off mechanism is actuated.

2

FIGURE 3 illustrates the manner of application of the device in a different position, such as is commonly encountered in the application of masking tape.

FIGURE 4 presents a fragmentary sectional elevation of the device illustrated in FIGURES 1, 2, and 3.

FIGURE 5 illustrates a modified form of the invention intended primarily for the application of electrician's tape.

FIGURE 6 illustrates a movable arm incorporated in 10 the device shown in FIGURE 4 for providing the final bearing point against the tape as it is being applied.

FIGURE 7 presents a fragmentary sectional elevation of the device shown in FIGURE 5, in the tape-stripping position.

FIGURE 8 illustrates the same device shown in FIGURE 7, with the cut-off mechanism in the actuated position.

FIGURE 9 illustrates a modification of the invention in which the cut-off mechanism incorporates a means 20 for removing insulation from wire. FIGURE 9 is in the retracted position of the knife.

FIGURE 10 illustrates the projected position of the 25 knife, and showing the relationship of the mechanism to a piece of wire from which insulation is being removed from the end prior to splicing.

Referring to FIGURES 1, 2, 3, 4, and 6, the illustrated device includes a frame generally indicated at 20 and including a container portion 21 which accommodates a roll of tape shown at 22 in FIGURE 4. The 30 central cylindrical member 23 provides a tubular journal on which the roll of tape 22 is loosely and rotatively received. According to the preferred method of manipulating the device, the tubular journal 23 can receive the thumb of the workman, with the fingers being in position adjacent the lateral extension 24 of the frame for the application of the necessary forces to strip the tape from the roll 22, and apply the necessary bearing to force it properly into engagement with the work surface 25 of a carton 26.

The lateral extension 24 of the frame is hollow and box-like in construction, and provides a sheltering conduit for the free end 27 of the tape after it has been stripped from the roll 22. In handling tape that has a very strong adhesive characteristic, such as the nylon-reinforced tape commonly used in the closure of carton flaps, it is desirable to incorporate a roller 28 immediately adjacent the periphery of the spool 22, with the free end 27 being threaded through the device in such a manner that the roller 28 bears upon the gummed surface. The effect of this arrangement is to securely 45 position the free end 27, and avoid fouling within the extension 24. The roller 28 is preferably rotatably mounted on a pin 29 secured in any convenient fashion at its opposite ends to the walls of the extension 24. The guide roller 30 is similarly mounted on the pin 31, and assists in positioning the outer portion of the free end 27 by providing an opening between the roller 30 and the edge 32 of the wall 33 of the extension 24 for the emergence of the tape. It would be obvious 50 from an inspection of FIGURE 4 that the positioning of the free end 27 in this manner will make the engagement of the tape with the next work surface a very simple procedure. The position of the cut-off mechanism is such that FIGURE 4 illustrates the approximate position 55 of the free end of the tape at all times.

After the free end 27 has been first placed in contact with a work surface, the device is manipulated so that the extension 24 is brought downward with respect to the tape (in the position shown in FIGURE 1), and the bearing roller assembly 34 will come into engagement with the back of the tape, which is normally not coated with adhesive. The roller assembly 34 is rotatably mounted

on the pivot arm 35; and this arm is itself rotatably supported on the pin 36 secured at opposite ends to the walls of the hollow extension 24. A torsion spring 37 surrounding the pin 36 has one end engaging the arm 35, and the opposite end engaging the tab 38 of the extension 24 to apply a biasing action tending to rotate the arm 35 in a counter-clockwise direction, as viewed in FIGURE 4. The arm 35 is best shown in FIGURE 6, and is essentially U-shaped in configuration. The back 39 connects the side flanges 40 and 41, and the spacing between these flanges is reduced at the outer end of the arm to provide for the support of the roller assembly 34 at intermediate points along the roller axis. This roller assembly is in the form of three segments 42-44, all being rotatably mounted on the pin 45. With this arrangement, the overall axial length of the roller assembly 34 is slightly less than the space between the side walls defining the extension 24, and bearing force is thereby applied to the free end 27 of the tape across substantially the full width thereof, and particularly at the outer edges.

When the desired length of tape has been applied, the cut-off mechanism of the device shown in FIGURES 1, 2, 3, 4, and 6 is actuated by manipulation of the sliding member 46, which is connected to the extension 24 by the rivets 47 and 48. Movement of the member 46 upwardly and to the right, as shown in FIGURE 4, will bring the cam portion 49 to bear against the underside of the back 50 of the lever 51, which is pivotally mounted on the pin 52 supported on the ears 53 which are integral with the extension 24. The lever 51 is preferably U-shaped in cross section, and includes the side flanges 54 and 55 connected to the back 50. The knife 56 is slidably mounted with respect to the extension 24 in the guideway formed by the opening between the end of the extension 24 and the bar 57. A tab 58 communicates the movement of the lever 51 to the knife 56, and the spring 59 biases the lever 51 in a direction to move the knife 56 to the retracted position shown in FIGURE 4. Actuation of the slide member 46 will project the knife 56 so that the V-shaped cutting edge 60 intersects the path of the tape, as shown in FIGURE 2.

Referring to FIGURES 5, 7, 8, 9, and 10, this modification of the invention is adapted for the handling of electrician's tape. The frame 61 includes a removable hollow journal member 62 which may be detached from the frame by manipulation of the latch 63. The frame has a hollow lateral extension 64 which is open on the underside, except for the transverse member 65, which terminates in the handle abutment 66. A positioning roller 67 is rotatably mounted on the pin 68 secured to the extension 64, and the tape 69 normally moves between the roller 67 and the pivoted plate 70 rotatably mounted on the pin 71. This pin is secured at its opposite ends to the side-walls of the extension 64, and also supports the torsion spring 72 acting between the top panel 73 of the extension and the plate 70 to apply biasing action in a counter-clockwise direction.

The cut-off mechanism in this modification of the invention includes a lever 74 having opposite side flanges 75 and 76 which also engage the pin 71 to form a pivotal mounting. The extension 77 of the lever provides an abutment against which forces can be applied to the right, with this abutment cooperating with the abutment 66 to provide points against which the pressure of the hand can be applied to resist the stripping forces necessary in applying the tape 69. Since the frame 61 does not contain an outer housing, the stripping of tape from the device necessitates leaving the roll 78 free from the palm of the hand so that the roll may rotate with respect to the frame. In the event that resistance is desired such as to increase the tension of the tape, a braking action can be applied by the hand to establish resistance of the rotation of the roll 78 with respect to the frame, and thus establish any desired degree of tension in the tape 69 as it is applied to the wire 79. It should also be noted that the position of

the portion 77 with respect to the pin 71 is such that any pressure applied as a result of the stripping forces will tend to rotate the lever to a position causing retraction of the knife 80, since the lever positions the knife as a result of the engagement of the tab 81. The bar 82 is spaced from the end of the extension 64, thus providing a guideway for the sliding movement of the knife 80, and also providing a bearing point with which forces can be applied to the tape 69. When the cutting mechanism is actuated by shifting of the thumb pressure over onto the portion of the lever to the left of the pin 71, as shown in FIGURE 7, the severing of the tape is instantly followed by a movement of the plate 70 to bring the free end of the tape into contact with the positioning roller 67, as shown in FIGURE 8. This leaves the tape free of any tendency to foul within the frame, and positions the end for ease of application to the next work surface.

When the device is used to handle electrician's tape, it is convenient to form the knife 80 and the bar 82 as shown in FIGURES 9 and 10 to incorporate an added utility to the device. The insulation 83 must frequently be removed from the metal wire 84 preparatory to splicing the wire, and the V-shaped cutting edge 85 of the blade 80 may be provided with a sharpened recess 86 which cooperates with a recess 87 in the bar 82 to form an opening which will just receive the metal 84 of the wire when the knife 80 is in the projected position shown in FIGURE 8. This has the effect of providing an annular cut around the insulation 83, and the device may be pulled to the right (as shown in FIGURE 10) with respect to the insulation, resulting in the stripping of the piece of insulation indicated at 88 from the end of the wire.

The return of the lever 74 to the FIGURE 7 position after the cut-off shown in FIGURE 8 can be accomplished either through the return of manual pressure to the portion 77, or through the use of an independent spring. The leaf spring 89 has a base 90 secured (by spot-welding or any other convenient means) to the lever 74. The free end 91 bears on the top panel 73 of the extension 64 to the left of the pin 71 to induce a clockwise rotation of the lever 74, as shown.

The sides of the extensions 24 or 64 may be formed to assist in aligning the dispenser with a strip to which tape is to be applied. This arrangement is shown best in FIGURE 4. The spaced walls 92 and 93 of the extension 24 are continued below the edge 32, as indicated at 94 and 95, to form spaced rails that may embrace a strip to be taped, or serve as a guide against a groove or ridge of a working surface to establish the tape position. This function is in addition to that of protecting the tape as it moves onto the point of application. These rails 94 and 95 are preferably rounded at the opposite ends as shown. The dispenser may be slid along the rounded side of the frame, with the tape properly applied by the bearing roller 34, and protected and positioned by the rails 94 and 95.

The particular embodiments of the present invention which have been illustrated and discussed herein are for illustrative purposes only and are not to be considered as a limitation upon the scope of the appended claims. In these claims, it is my intent to claim the entire invention disclosed herein, except as I am limited by the prior art.

I claim:

1. A tape dispenser, comprising:
a frame including a disengageable tubular journal portion for rotatably receiving a spool of tape, said frame having a lateral hollow extension forming a cantilever beam;
guide roller means rotatably mounted in said frame adjacent the normal position of the periphery of a spool mounted on said journal portion;
an arm rotatably mounted in said extension; biasing means urging said arm to a position projecting from said extension;
bearing roller means rotatably mounted at the end of

said arm for movement with respect to said extension, said roller being engaged by said arm at intermediate points along the length of said roller means, said roller means having an axial length substantially equal to the inside width of said extension; 5 cut-off means including a knife member having a V-shaped cutting edge and slidably mounted in said extension adjacent the end thereof remote from said journal portion, said knife member being disposed transversely to the normal path of movement of said tape, and movable to a position intersecting the same;

said cut-off means also including biasing means tending to retract said knife member to a position wherein the cutting portion thereof is disposed within said frame. 15

2. A tape dispenser, comprising:

a frame for rotatably receiving a spool of tape, said frame having a lateral hollow extension forming a cantilever beam; 20

an arm movably mounted in said extension; biasing means urging said arm to a position projecting from said extension;

bearing roller means rotatably mounted at the end of said arm for movement with respect to said extension, said roller being engaged by said arm at intermediate points along the length of said roller means, and said roller means having an axial length substantially equal to the inside width of said extension; and 25

cut-off means including a knife member mounted in said extension adjacent the end thereof remote from said journal portion, said knife member being dis-

10

20

30

posed transversely to the normal path of movement of said tape.

3. A tape dispenser, comprising:
a frame including a tubular journal portion for rotatably receiving a spool of tape, said frame having a lateral hollow extension forming a cantilever beam; and

cut-off means including a knife member movably mounted in said extension adjacent the end thereof remote from said journal portion, said knife member being disposed transversely to the normal path of movement of said tape, and movable to a position intersecting the same,

said cut-off means also including lever means pivotally mounted on said extension and engaging said knife member at a point on said lever means remote from the pivotal mounting thereof, said cut-off means also including a cam member slidably mounted on said extension for actuating said lever.
